TOY GUN

Otto A. Langos, Chicago, Ill.

Application February 5, 1948, Serial No. 144,301

Term of patent 14 years

(Cl. D34—15)

To all whom it may concern:

Be it known that I, Otto A. Langos, residing in the city of Chicago, county of Cook, State of Illinois, have invented a new, original, and ornamental Design for a Toy Gun, of which the following is a specification, reference being had to the accompanying drawing, forming a part thereof, in which:

Fig. 1 is a side elevational view of the gun;
Fig. 2 is a plan view of the gun; and

Fig. 3 is an end elevational view of the gun.

The dominant features of my design are shown in solid lines in the drawing.

The paper tape ammunition is shown in dotted lines in Fig. 1 for illustrative purposes only.

I claim:

The ornamental design for a toy gun, substantially as shown and described.

OTTO A. LANGOS.
